UNITED STATES PATENT OFFICE.

ANDREW L. MARGACH, OF UTICA, NEW YORK, ASSIGNOR TO MERGENTHALER LINOTYPE COMPANY, A CORPORATION OF NEW YORK.

TYPE OR MATRIX.

1,105,676.

Specification of Letters Patent.

Patented Aug. 4, 1914.

Application filed May 19, 1913. Serial No. 768,437.

To all whom it may concern:

Be it known that I, ANDREW L. MARGACH, a citizen of the United States, residing at Utica, in the county of Oneida and State of New York, have invented certain new and useful Improvements in Type or Matrices, of which the following is a specification, reference being had therein to the accompanying drawing.

My invention relates to typographical machines, such as linotype machines of the general organization represented in Letters Patent of the United States to Ottmar Mergenthaler, Serial No. 436,532, wherein calculating matrices are released from a magazine, in the order in which their characters are to appear in print, and then assembled in line, the composed line transferred to the face of a slotted mold, the mold filled with molten metal to form a slug or linotype against the matrices which produce the type characters thereon, and the matrices thereafter returned through a distributing mechanism to the magazine from which they started.

More particularly, the invention relates to a special form of matrix for use therein, comprising a plurality of relatively movable or interchangeable character-bearing sections constituting a composite matrix which is adapted for producing special or unusual characters, such for instance, as fractions of any numerical value.

Referring to the drawings, I have shown my invention in preferred form and by way of example, and as applied to the kind of matrix shown and described in the said Mergenthaler patent, or as employed in the commercial linotype machine, but obviously many changes and variations therein, and in its mode of application, will suggest themselves to those skilled in the art without departing from the limits of the invention. Thus it may be used in connection with other styles of typographic machines, or with type casters, type setters and the like, or any machines which handle type or dies instead of matrices.

Generally speaking, I desire it to be understood that I do not limit myself to the specific forms and embodiments herein described.

In the accompanying drawings: Figure 1 is an elevation of an assembled line of matrices in which certain of the individual

matrices have my invention embodied therein; Fig. 2 is a perspective view of my improved matrix in one form, the sections of the same being shown separated from each other; Fig. 3 is a similar view of another form of the matrix; Fig. 4 is an elevation of a series of the body portions of the composite matrices, one body portion being shown partly in section; Fig. 5 is an elevation of a series of the movable sections or inserts; Fig. 6 is a similar view of the inserts of a different width; Figs. 7 and 8 are perspective views of other modifications of the matrix, the inserts being shown separated from the body portions; Fig. 9 is a perspective view of still another modification, showing the sections of the matrix assembled in operative relations to produce a composite structure; and Fig. 10 is a perspective view of one of the inserts of the form shown in the preceding figure.

Referring to the drawings; my improved matrix comprises in its simplest form as shown in Fig. 3, a plurality of relatively movable sections 1 and 2, the section 1 being the body portion of the matrix and the section 2 the insert, which latter is adapted to be seated in a recess 3, in the body portion so that the whole will form a self-contained composite structure in which the adjacent character-bearing faces 4 and 5 of the body portion and insert respectively, will extend in a common plane. To adapt the sections to be thus assembled and held, the insert is, in this instance, formed in its upper edge with a V-shaped groove 6, adapted to receive a rib 7, on the upper wall of the recess 3, and the lower edge of the insert is formed with a V-shaped rib 8, adapted to enter a correspondingly formed groove 9, in the bottom of the recess. These engaging parts are so fitted that when the insert is slid back into the recess, the frictional engagement of the ribs and grooves will prevent the displacement of the insert in a forward direction, while the projection of the ribs into the grooves will prevent the insert from displacement in a lateral direction. In the example shown, the body portion of the matrix is provided with the numeral-character 2, and the insert with the numeral-character 1, so that, with the insert in place in the body portion, a matrix is formed with the composite numeral-character 3. By employing

a series of inserts, 2, 2, etc., of this form as shown in Fig. 5, bearing different numerals, and by interchanging them for the one shown in Fig. 3, different fractions may be produced on the composite matrix. So also the combinations may be increased by employing a series of interchangeable body portions, 1, 1, etc., bearing different numerals as shown in Fig. 4.

10 In order to produce fractions in which the denominator contains a greater number of numerals than the numerator, and in which the numerals will bear a symmetrical relation to each other, for instance, such a 15 fractions as $\frac{1}{16}$ the composite matrix may consist as in Fig. 2 of a plurality of body portions, two in the present instance, 1^a, 1^a, each with a numeral character, and a single insert, 2^a, of a width equal to the combined 20 widths of the body portions and having a single character, the insert being formed with two grooves, 6^a, 6^a, and two ribs, 8^a, 8^a, to coöperate with the ribs 7^a, 7^a, and 25 grooves 9^a, 9^a on the body portions. When the single wide insert is seated in the recesses, 3^a, 3^a in the two body portions, the latter will be connected together by the insert and the several connected sections will constitute a composite matrix with the composite character $\frac{1}{16}$ thereon. By employing 30, as in the first instance described, a series of inserts of this form as shown in Fig. 6, interchangeable with each other and bearing different numerals, different fractions may be produced on the composite character. So also by employing in connection with these inserts, the different interchangeable body portions of the form shown in Fig. 4, additional forms of 35 fractions may be produced on the composite matrix.

In Fig. 8 a construction is shown which is a reversal of that just described. In this case there are two inserts, 2, 2, of the form shown in Figs. 3 and 5 fitted to a single body portion, 1^b, which body portion is of a width equal to the combined widths of the inserts, the inserts each being provided with a numeral-character and the body portion being provided with a single character. The parts are formed as in the other case described, with interfitting grooves and recesses, two grooves, 9^b, 9^b and two ribs, 7^b, 7^b on the body portion to coöperate with 50 the ribs and grooves on the individual inserts. When the parts are assembled, the two inserts will be held together by the single body portions and a composite matrix will be produced with the composite fraction, 55 in this case $\frac{1}{3}$, the numerator thus having a greater number of numerals than the denominator. Various other combinations of numerals to produce different forms of fractions may be produced by providing, in connection with the interchangeable inserts of

Figs. 5 and 8, a series of interchangeable body portions of the form shown in Fig. 8 with different characters thereon.

In Fig. 7 a construction of composite matrices is shown, comprising a plurality of body portions, 1, and a corresponding number of inserts, 2, each of said parts having a character thereon to produce a fraction in which the numerator and denominator have the same number of numerals. In this case 70 the inserts and body portions are formed with interfitting ribs and grooves, as in the first instance, to adapt the inserts to be held in their proper positions in the recesses in the body portions, but inasmuch as the inserts are disconnected from each other, they will not act to hold the body portions together as in the construction of Fig. 2. Therefore, additional means are provided for this purpose, which means, in the present instance, are in the form of pins, 10, extending transversely through holes in the body portions and securing them together in the form of a composite matrix, bearing, in this instance, the fraction $\frac{1}{11}$. 80

In Fig. 9 I have shown a different construction of the body portions and inserts to adapt them to be assembled, both as regards the attachment of the individual inserts to the individual body portions, and the attachment of the connected bodies and inserts together. In this figure is shown a composite matrix made up of three body portions, 1^c, 1^c, 1^c, and three inserts, 2^c, 2^c, 2^c, all connected together in the form of a single 100 composite structure, two of the inserts having characters thereon and the other being a blank, and all of the body portions being provided with characters, thereby producing a fraction with two numerals in the numerator and three numerals in the denominator, the fraction in this particular instance being $\frac{1}{24}$. Each of the body portions is formed with a recess 3^c having a notch 11, in its upper wall and having its 110 bottom sloping downwardly toward the front. The insert is of a corresponding form as shown in Fig. 10 with a tooth 12, adapted to enter the notch 11 and with its lower end beveled to fit the bottom of the 115 recess. The inserts are held in the notches in the recess in the body portions by pins 13 and 14 driven in between the edges of the inserts and the walls of the recess. With a 120 number of body portions and inserts assembled for conjoint use as shown, the pins engaging between all of the body portions and inserts will act to connect the entire series together in the form of a single structure or a composite matrix. It will be understood 125 of course that a number of body portions and inserts may be provided of the form shown in Fig. 9 and bearing different numerals or characters and also blanks, and being interchangeable one for the other so 130

that by assembling them in different combinations practically all forms of fractions may be produced either with the same number of numerals in the numerator and denominator or different number of numerals in the numerator and denominator.

I have illustrated and described different constructions of the sectional parts to adapt them to be assembled and held in different relations, but it will be manifest to those skilled in the art that other means and methods may be employed for the purpose, the particular constructions being merely by way of example.

15 In order that in producing fraction characters by my improved matrix, provision will be made for forming the usual horizontal line dividing the numerator and denominator I propose to chamfer the adjacent edges of the inserts and body portions as at 15 and 16 in the several figures with the result that these chamfered edges will conjointly form an indentation, which in the cast type will result in a printing line. It is obvious however that the indentation may be formed wholly either in the insert or in the body portion of the matrix.

Matrices constructed in accordance with the foregoing description may be assembled 30 and employed in the justified line with the usual and ordinary matrices A as shown in Fig. 1, and they may either be inserted by hand in the line during composition and removed therefrom after the casting operation, or they may be circulated and distributed with the other matrices, in which case they will be provided with a distributing combination B as shown by dotted lines in Figs. 3 and 9 designed to coöperate with 40 the well-known distributing rail or bar of the machine, with which the usual and ordinary matrices coöperate.

Having thus described my invention what I claim is:

45 1. A type or matrix constructed for circulation in typographical composing machines, comprising a body portion having a character and a movable section provided with an associated character.

50 2. A type or matrix constructed for circulation in typographical composing machines, comprising a plurality of relatively movable sections provided with characters.

55 3. A type or matrix constructed for circulation in a typographical composing machine, comprising a body portion and a plurality of movable character-bearing sections.

40 4. A type or matrix adapted for use in typographical composing machines, comprising a body portion provided with a character, and a plurality of movable sections having associated characters.

45 5. A type or matrix adapted for use in typographical composing machines, comprising a plurality of separably connected

body portions, and a coöperating movable character-bearing section.

6. A type or matrix constructed for circulation in typographical composing machines, provided with a character made up 70 of elements, said matrix comprising a plurality of relatively movable sections, each having at least one of said elements.

7. A type or matrix constructed for circulation in typographical composing machines, provided with a character made up 75 of associated elements, said matrix comprising a plurality of relatively movable sections, each having at least one of said elements.

8. A type or matrix constructed for circulation in typographical composing machines, provided with a character made up 80 of a plurality of elements, said matrix comprising a body portion having at least one 85 of said elements, and a movable section having also at least one of said elements.

9. A type or matrix adapted for use in typographical composing machines, comprising a plurality of separately connected 90 body portions, and a plurality of coöperating movable character bearing-sections.

10. A type or matrix adapted for use in typographical composing machines, comprising a plurality of separably connected 95 body portions provided with characters, and a plurality of coöperating movable character-bearing sections.

11. A type or matrix adapted for use in typographical composing machines, comprising a plurality of separably connected 100 body portions provided with associated characters, and a movable section having a character adapted to be associated with those in the body portions.

12. A type or matrix adapted for use in typographical composing machines, comprising a plurality of separably connected body portions provided with associated characters, and a plurality of movable sections having characters adapted to be associated with those on the body portions.

13. A type or matrix constructed for circulation in typographical composing machines, provided with a character made up 115 of associated elements, said matrix comprising a plurality of relatively movable sections, each having one of said elements.

14. A series of type or matrices constructed for circulation in typographical composing machines, the individual matrices being composed each of a plurality of sections interchangeable with the sections of the other matrices to produce different composite characters.

15. A matrix comprising a body portion and a relatively movable section sustained thereby, said parts constructed to conjointly present a formative indentation to produce a printing line on the type.

16. A matrix comprising a body portion and a relatively movable section sustained thereby, said parts having their adjacent edges chamfered to conjointly present a 5 formative indentation to produce a printing line on the type.

17. A series of character bearing sections interchangeable with each other, and adapted to be removably carried by other character bearing sections to produce different kinds of composite matrices, said matrices being formed for circulation in typographical composing machines.

18. Two sets or series of character bearing sections, one set being adapted to be removably carried by the other set, and interchangeable with each other to produce different kinds of composite matrices, said matrices being formed for circulation in typographical composing machines.

19. A series or set of sections having the full complement of digits, in combination with a second set of sections also having the full complement of digits and adapted to removably support the sections of the first set in such relations that the digits of one set will appear above the digits of the other set to produce numerical fractions, and the supported sections being interchangeable with each other to produce composite matrices representing fractions of different numerical values, and said supporting sections being formed for use in typographical composing machines.

In testimony whereof I have affixed my 26 signature in presence of two witnesses.

ANDREW L. MARGACH.
